UNITED STATES PATENT OFFICE.

WILLIAM MASON, OF NEW HAVEN, CONNECTICUT, ASSIGNOR TO THE
WINCHESTER REPEATING ARMS CO., OF NEW HAVEN, CONNECTICUT
A CORPORATION.

AUTOMATIC FIREARM.

No. 854,707.

Specification of Letters Patent.

Patented May 21, 1901

Application filed February 12, 1901, Serial No. 300,632.

To all whom it may concern:

Be it known that I, WILLIAM MASON, a citizen of the United States, residing at New Haven, in the county of New Haven and State of Connecticut, have invented a new and useful Improvement in Automatic Firearms; and I do hereby declare the following when taken in connection with the accompanying drawings, and the letters of reference marked thereon, to be a full, clear, and exact description of the same, and which said drawings constitute part of this specification, and represent, in—

Figure 1 a broken view in right hand side elevation of a gun embodying my invention and represented as closed. Fig. 1^a a broken sectional view on the irregular line *x*—*y* of Fig. 1, showing the trigger-lock. Fig. 2 a broken plan view showing the same portion of the gun. Fig. 3 a broken view partly in vertical longitudinal section and partly in elevation, looking into the gun from its right hand side and showing it closed. Fig. 4 a broken view partly in vertical longitudinal section and partly in side elevation, this view constituting, in effect, an extension of the forward end of Fig. 3. Fig. 5 a broken view partly in plan and partly in horizontal section, and made with particular reference to showing the locking-slide latch and the bolt-stop functioning as a cartridge-indicator. Fig. 6 a view corresponding to Fig. 3 but showing the action-mechanism recoiled as after firing. Fig. 7 a view corresponding to Fig. 4 and virtually constituting an extension of Fig. 6, the parts being shown in the positions taken when the action mechanism is recoiled as after firing. Fig. 8 a view corresponding to Figs. 3 and 6 but showing the gun open. Fig. 9 a view in vertical cross section on the line *a*—*b* of Fig. 3. Fig. 10 a corresponding view on the line *c*—*d* of Fig. 3 showing the magazine closed. Fig. 11 a corresponding view on the same line, showing the magazine open with a clip inserted into the clip-holder preparatory to charging the magazine. Fig. 12 a view on the line *e*—*f* of Fig. 3 looking at the front end of the receiver which is shown in elevation. Fig. 13 a view in vertical cross-section on the line *g*—*h* of Fig. 4. Fig. 14 a detached view in front elevation of the trigger-guard. Fig. 15 a detached view in vertical longitudinal section, of the receiver,

looking into the same from right to left showing it stripped. Fig. 16 a detached plan view of the receiver. Fig. 17 a detached view of the receiver in front elevation. Fig. 18 a view thereof on the line *i* of Fig. 15. Fig. 19 a detached reverse plan view of the barrel-extension. Fig. 20 a plan view thereof. Fig. 21 a view thereof in right hand side elevation. Fig. 22 a view thereof in front elevation. Fig. 23 a view thereof in rear elevation. Fig. 24 a view thereof in vertical longitudinal section, looking from right to left. Fig. 25 a corresponding view looking from left to right. Fig. 26 combines detached views in right hand side elevation, in plan and in front and in rear elevation of the rotary breech-lock. Fig. 27 a detached plan view of the breech-block. Fig. 28 a view thereof in vertical longitudinal section, looking from right to left. Fig. 29 a view thereof in rear elevation. Fig. 30 a detached plan view of the locking-slide. Fig. 31 a view thereof in right hand side elevation. Fig. 32 a view thereof in rear elevation. Fig. 33 a view thereof in front elevation. Fig. 34 a detached plan view of the locking-slide link. Fig. 35 a detached plan view of the action handle. Fig. 36 a view thereof in side elevation. Fig. 37 a view thereof in rear elevation. Fig. 38 a view thereof in front elevation. Fig. 39 a detached plan view of the cartridge indicator. Fig. 40 a view thereof in rear elevation. Fig. 41 a detached view of the magazine-latch. Fig. 42 a side view of the magazine-latch plug. Fig. 43 a detached plan view of the trigger. Fig. 44 a view thereof in right hand side elevation. Fig. 45 a detached plan view of the sear. Fig. 46 a view thereof in right hand side elevation. Fig. 47 a detached plan view of the front unlocking-lever. Fig. 48 a view thereof in right hand side elevation. Fig. 49 a detached plan view of the rear locking lever. Fig. 50 a view thereof in right hand side elevation. Fig. 51 a plan view of the ejector. Fig. 52 a view thereof in right hand side elevation. Fig. 53 a view thereof in front elevation. Fig. 54 a view thereof in rear elevation. Fig. 55 a view in rear elevation of the swinging magazine stripped. Fig. 55^a a detached view of the magazine in elevation, with its rear wall removed to show the double column of cartridges. Fig. 56 a view thereof in front elevation. Fig.

n horizontal section on the line $k-k$ of Fig. 56, showing the recess in the forward end of the magazine for the reception of the magazine-latch. Fig. 58 a detached view in elevation of the pivotal clip-holder. Fig. 59 a view thereof in side elevation. Fig. 60 a plan view thereof.

invention relates to an improvement in class of small arms in which the barrel is at the moment of firing and operates action-mechanism in ejecting the spent and introducing a loaded cartridge into in-chamber, the object being to produce pact and reliable arm constructed withular reference to the employment of a magazine adapted to be loaded from

th these ends in view my invention con-
n a gun having certain details of con-
ion and combinations of parts as will be
afters described and pointed out in the

carrying out my invention as herein set forth, I employ a recoiling barrel 2 provided with its breech end with a depending lug 3 having a central opening to receive a tubular guide-rod 4 the rear end of which is threaded for being screwed into the rear end of the receiver 5. The operating-spring 6 of the gun encircles the rear portion of the rod 4 and is abutted at its rear end against the receiver and at its forward end against the rear face of the lug 3 which rides to and fro upon the rod as the barrel re- and returns to its normal position. The rear end of the rod extends through and supports the forward end of the forearm 7 the rear end of which is supported in the usual manner by the front end of the receiver. A band applied to the extreme forward end of the forearm holds the same back in place. The forward end of the forearm is formed with a recess 9 for the reception of a sleeve- buffer 10 mounted upon the forward end of the rod 4 and located in position to be engaged by the forward face of the lug 3 when the barrel is returned to its normal position by the operating-spring 6.

The barrel 2 is mounted in the forward end of the barrel-extension 11 (Figs. 19—23) which moves back and forth in the receiver 5, the motion being formed with guide ribs 12 engaged into corresponding grooves 13 respectively formed in the inner faces of the right and left side walls of the receiver. The said extension is formed with a central vertical passage 14 through which the cartridges are shoved upward into position to be shoved forward into the barrel, this opening being closed on either side, at its rear end, by cartridge-stop ribs 15 and 16 which prevent the cartridges from being lifted upward out of the barrel by the spring 17 of the cartridge-carrier. This passage 14 is entirely closed by the catch-block 19 (Figs. 27—29) when the gun

is closed. The inner face of the side walls of the barrel-extension are formed with corresponding locking-recesses 20 for the reception of the opposite ends 21 and 22 of a rotary breech-lock 23 (Fig. 26) which is mounted upon the locking-slide 24 (Figs. 30—33) which is formed at its forward end with spiral ribs 25 taking into corresponding grooves 26 leading out of the central opening 27 of the breech-lock 23 and also extending through a hub 28 formed upon the forward face of the block and furnished with grooves 29, 29, for the clearance of the cartridge-stop ribs 15 and 16 aforesaid when the lock is turned into its unlocked position and is moved back and forth with respect to the barrel-extension. The shock of recoil is taken by the rear faces of the ends 21 and 22 of the rotary breech lock 23 and the rear walls of the locking-recesses 20 in the extension 11. 70 75 80 85

For the reception of the rotary breech-lock 23, the breech-block 19 is formed with a lateral opening 30 extending through it from side to side and having a forward extension 31 for the reception of the hub 28 of the lock 90 and a rearward extension 32 for the reception of an assembling collar 33 mounted upon the locking slide 24 at a point directly back of the lock 23 and exactly corresponding in width to the length of the hub 28 and the 95 depth of the extension 31. By removing the pin 34 which confines the locking-slide 24 in the breech-block 19, the slide may be pulled back out of the block. The collar 33 may then be removed which permits the rotary 100 breech-lock 23 to be drawn back sufficiently to clear its hub 28 from the extension 31 of the recess 30. When so drawn back the lock 23 may be drawn laterally out of the breech-block. On the other hand, when the lock 23 105 has been inserted into the passage 30 and moved forward to enter its hub 28 into the extension 31, the assembling collar 33 is applied to hold it forward in its proper position. The top of the locking slide 24 is formed with 110 a slot 35 receiving a pin 34 limiting the longitudinal movement of the slide by the engagement of its end walls with the opposite faces of the pin.

At its rear end the locking-slide is connected by a pin 36 with the yoke-shaped forward end of the locking-slide link 37 (Fig. 34) the rear end of which has ball-and-socket connection with the forward end of a follower 38 located in the upper tang 39 of the gun and operated by a helical action-closing spring 40 which extends rearward into the butt-stock and which exerts a constant effort through the said link 37 to push the slide 24 forward and hence the breech-block 19. 125

The breech-block 19 is formed upon its sides with guide-ribs 41, 41, which take into corresponding grooves 42, 42, formed in the inner faces of the side walls of the receiver. The breech-block is also formed with bearing 130

surfaces 43, 43, adapting it to ride upon the barrel-extension 11 as shown in Fig. 9 when moving into its closed position. Furthermore, the breech-block extends downward through the vertical passage 14 of the barrel-extension so as to completely occupy the same when the block is closed, the lower face 44 of the block engaging with the hammer 45 for cocking the same.

10 The firing pin 46 is located in a central passage 47 in the locking-slide 24 from the forward and rear ends of which it projects, its rear end being struck by the forward face of the hammer for exploding the cartridges.

15 When the gun is fired, the barrel 2, barrel-extension 11, breech-block 19 and locking-slide 24 recoil together, compressing the spring 40. When these parts reach the limit of their rearward excursion, as shown in Fig.

20 6, the rear end of the rear unlocking-lever 48 is lifted by the spring 49 thereof into engagement with the beveled forward end of a locking-rib 50 formed upon the rear end of the right hand side of the locking-slide 24, where-

25 by the locking-slide is temporarily caught and retained in its recoiled position. The operating-spring 6, which was compressed during the recoil, now operates to pull the barrel-extension 11 forward and with it the breech-block 19, which in turn imposes enough forward draft upon the rotary breech-

lock 23 to cause the same to be rotated by the spiral ribs 25 of the locking-slide 24 now firmly held, as stated, by the lever 48, where-

30 35 by the block is turned into its unlocked position in which its ends are cleared from the recesses 20, 20, in the barrel-extension,

which, being thus released, moves forward with the barrel, leaving the breech-block in

40 the position shown by Fig. 8.

Just before the barrel-extension 11 reaches the limit of its forward movement, a toe 51 depending from its right hand side, engages with the rear edge of the upper arm of the front unlocking-lever 52 and rocks the same upon the hammer-pin 53 upon which it is mounted, and as the lower arm of the said lever 52 enters the forward end of the rear unlocking-lever 48, the same will be rocked 50 enough to clear its rear end from the locking-rib 50 of the locking-slide 24.

As shown in Fig. 8, the lever 48 is just about to release the locking-slide which is then moved forward by the spring 40 through the medium of the link 37, into the position in which it is shown by Fig. 3, together with the breech-block; but in order to prevent the locking-slide 24 from moving forward with respect to the breech-block 19 so as to rotate 55 the breech-lock 23 prematurely, I employ a locking-slide latch 54 mounted upon a pin 55 and located in a recess in the left hand side of the breech-block. A small spring 56 carried by the breech-block engages with the forward end of the latch 54 and exerts a con-

stant effort to swing its notched rear edge inward into engagement with the forward edge of the locking-slide 24. (Fig. 5). When the breech-block 19 is drawn forward by the spring 6 with the barrel-extension 11 for rotation of the breech-lock 23, the latch 54 engaged with the forward end of the slide whereby the breech-block and locking-slide are spaced, as it were, and the locking-slide prevented from moving forward with respect to the breech-block when the two parts being moved forward together by the actuating spring 40. This spacing of the locking-slide and breech-block is maintained until after the breech-block has reached its closed position at which time the rear breech-lock 23 is brought into registration with the two locking-recesses 20 in the barrel-extension 11. Just as soon as this is in place, the forward end of the latch 54 engaged with a beveled surface 57 at the forward end of a groove 58 in the left hand wall of the barrel-extension 11 (Fig. 5), whereby the forward end of the latch is forced inward against the tension of the spring 56 and the rear of the latch disengaged from the forward edge of the locking-slide 24 which is then free to be pushed forward with respect to the breech-block by the spring 40, this movement of the locking-slide effecting rotation of the breech-lock 23 into its locked position.

A hammer 45 having a hammer-spring 49 is formed with a cocking-notch 60 entering the nose of a sear 61 (Figs. 45—46) hung on a pin 62 also serving for the trigger 63 (Figs. 43—44) and mounted in the trigger-guard 64 which is secured in place by a rear tang 64 which is secured in place by an assembling screw 65. The rear end of the sear is made blade-like and therefore laterally flexible and terminates in a lug 66 normally located directly over a bearing surface 67 at the rear right hand corner of the trigger. When the trigger is pulled, the said surface 67 lifts directly against the lower edge of the lug 66, whereby the end of the sear is lifted and its nose is pressed preparatory to moving out of the cocking-notch 60 in the hammer. The sear is being lifted, a fixed pin 69 mounted in the rear end side wall of the trigger-guard and having the lower face of its projecting inner end beveled, is gradually pushing the lug 66 of the sear inward out of registration with the surface 67 of the trigger. The flexible blade-like rear portion of the sear is springing laterally for this purpose. The surface 67 lifts against the lug 66 until the nose 68 of the sear has been moved out of the cocking-notch 60 in the hammer. Thereafter this takes place, the pin 69 continues its work by pushing the lug 66 inward of the surface 67 which rises outside. From this moment, the sear is no longer controlled by the trigger which cannot ag-

sear for releasing the hammer until the sear has been returned to n over the surface 67 of the trigger. s the trigger has been "let go" by f the gun, the trigger-spring 70 op- depress the trigger, while the sear- operates to depress the sear. As s depressed with respect to the pin vel thereof then constitutes a clear- allows the blade-like portion of the assert itself and spring from left to thereby the lug 66 is returned to its position directly over the surface 67, ng the sear in position to be opera- n by the trigger, which, however, 'let go' as described, before it can s control of the sear after the firing i. In other words, it is imperative een every firing of the gun the trig- et go". This is not broadly new m only my particular way of accom- he result. forward end, the trigger is formed ger 72 (Fig. 44) having a semicircu- 73 conforming in curvature to the of a longitudinally movable trig- 74 mounted for transverse move- he forward end of the lower tang 64, ith a circumferential groove 75 (Fig. imited in endwise movement by a n 76. In the normal position of the its groove 75 is registered with the . When, however, it is desired to trigger, the lock 74 is pushed from ght, whereby its groove 75 is carried gistration with the notch 73 and the ture of the lock brought into ent with the edge of the notch 73 so trigger cannot be pulled. hammer 45 is cocked during the rear- cusion of the breech-block 19 by the ent with its firing face, of a cam 77 at the rear end of the locking-slide hammer being cammed back against on of the hammer-spring 59 which is ed with it by a stirrup 79. sure the operation of the sear 61, in its nose 68 into the cocking-notch 60 hammer 45 in case the sear-spring 71 for any reason, fail to act, I form the at its rear end with a fin 80 which, e hammer is approaching its cocked , engages directly with the upper the blade-like rear end of the sear 61 at a point to the rear of the pivot 62 nsures the lifting of the nose 68 of the o position to enter the cocking-notch e hammer. rein shown, the gun is provided with ing box-magazine 81 (Figs. 55—56) t in width and depth to receive two columns of cartridges which are fed rom above either manually or from a ny approved construction. The clip n shown is like the clips used with the

well-known Mauser gun, but I am not, of course, confined to the use of such clips.

The magazine 81 is provided at its forward end with a trunnion 83 flattened in the horizontal plane and turning in a circular bearing- 70 hole 84 formed in the front end of the receiver and entered through a vertical slot 85 made wide enough for the flatwise passage of the trunnion. At its rear end the magazine 81 is provided with a trunnion 86 flattened in 75 the horizontal plane to correspond to the trunnion 83 and turning in a circular bearing-hole 87 (Fig. 14) into which it is entered from below through a vertical slot 88 made wide enough to receive it flatwise, the said 80 bearing-hole 87 and slot 88 being located in the forward end of the trigger-guard 64.

To put the magazine into the receiver it is presented thereto at a right angle, whereby its trunnions 83 and 86 are presented flat- 85 wise to the slots 85 and 88 through which they are then entered into the bearing-holes 84 and 87. Now when the magazine is swung upward into any of the positions shown in the drawings, its trunnions are 90 swung across the slots 85 and 88 in such a way that they are prevented from escaping therefrom.

To constrict the mouth of the magazine for the central delivery therefrom of the car- 95 tridges, I form it with two inwardly inclined bevels 89, 90, extending forward from its rear end, the cartridges in the left hand column being deflected inwardly by the bevel 89, and those in the left hand column being deflected 100 inwardly by the bevel 90. The cartridges are thus fed one at a time out of the maga- zine first from one column and then the other under the upward lift of the spring 17 of the carrier 18 which is furnished at its ends with 105 antifriction rollers 18^a riding upon the inclined inner surfaces of the end walls of the magazine. In this connection I wish to par- ticularly point out that the upper end of the magazine, when the same is in its closed po- 110 sition, is so far below any portion of the breech-block 19 that the magazine may be swung into its open or closed positions en- tirely irrespective of the position of the block, whereas if the upper end of the magazine 115 were extended up into the path of the breech- block, the magazine could then be swung into its open and closed positions only when the breech-block was open or at the limit of its rearward excursion. In a manually oper- ated gun this might not be objectionable, but in an automatic gun it would involve the objection of compelling the user to open the gun by the exertion of enough effort to over- 120 come the power of its breech-closing spring 125 against which the block would have to be drawn back to permit the magazine to be swung open. I am enabled to make the magazine clear the breech-block at its upper end as described for the reason that I do not 130

rely upon any part of the magazine for the retention of the cartridges against the upward lift of the spring 17 of the cartridge-carrier 18, whereas the majority of the box-magazines now in use have the upper ends of their side walls curved inward to form cartridge-stops under which the uppermost cartridge is pushed forward horizontally out of the magazine by the lower portion of the front face of the breech-block. I make the opening and closing of the magazine entirely independent of the position of the breech block, by providing for the stopping of the cartridges against the upward lift of the spring 17 of the cartridge carrier 18, independently of the magazine. As herein shown this provision consists of the cartridge-stop ribs 15 and 16 located in the barrel-extension 11. When the magazine is in its closed position, the cartridges are fed entirely out of its upper end and engaged with the lower faces of these ribs which hold the cartridges in position to be "picked up" by the breech-block and pushed forward horizontally into the gun barrel. The upper faces of these ribs provide for using the gun at any time as a "single-loader" whether the magazine is in the gun or not.

To limit the swinging movement of the magazine, I employ a magazine-latch 91 (Fig. 41) mounted in a plug 92 (Fig. 42) screwed into the front end of the receiver and projecting forward into the forearm 7. At its rear end the latch has a rounded nose 93 adapted to enter a segmental groove 94 (Fig. 56) formed in the front end of the magazine and having circular depressions 95, 96 at its ends for the reception of the nose 93 which is forced into them by a spring 97 encircling the main body of the latch the movement of which is limited by a stop-pin 98 mounted in the plug 92 and entering a notch 99 in the forward end of the latch. At its rear end the latch is provided with a knurled finger-piece 100 extending outward through a slot 101 in the right hand wall of the receiver to permit the latch to be manually operated for releasing the magazine preparatory to swinging it outward into its open position (Fig. 11) in which it is charged.

For charging the magazine, I employ a pivotal clip-holder 102 (Figs. 58, 59 & 60) having a trunnion 103 entering a hole 104 in the rear wall of the magazine 81 from the rear end of the said opening, the holder 102 being held in place by the entrance of its middle portion into a vertical slot 105 in the upper right hand corner of the rear wall of the magazine. The outer end of the clip-holder 60 is formed with a clip receiving slot or passage 106 virtually corresponding in form to the cross sectional form of a clip. At its lower end the clip-holder is formed with a rearwardly projecting semicircular lug 107 the flat face of which is engaged by the free end

of a U-shaped spring 108 located in a shall recess 109 in the rear face of the rear end the magazine. When the magazine is swung into its open position, the end of the spring 108 coacting with the flat face of the lug, operates to swing the clip-holder on its trunnion 103 into the position in which the holder is shown in Fig. 11 in which its passage 106 is align with the chamber of the magazine. With the clip-holder in this position, a clip 82 or the equivalent thereof, is inserted into the passage 106 of the clip-holder after which the cartridges in the clip are stripped therefrom in the magazine. Now when the magazine is swung back into its closed position, as shown by Fig. 10, the inner edge of the clip-holder engages with the lower edge of the right hand wall of the receiver at about the point 101 (Fig. 10) whereby the clip-holder is swung its trunnion 103 into its normal position, shown in Fig. 10, against the tension of the spring 108 which is nearly ridden off the flat face of the semicircular lug 107.

For access to the magazine for swinging from left to right into its open position from the position of Fig. 10 to the position of Fig. 11—the left hand side wall of the receiver 7 is formed with a finger-opening 111 (Fig. 15) through which the fingers are inserted for pushing the magazine from left to right.

To advise the sportsman when the cartridges in the magazine are exhausted, I employ a part 112 (Figs. 5 & 39) which functions as a bolt-stop but serves as a cartridge indicator, by which term I shall hereafter speak of it. This part is located in a longitudinal recess 113 in the right hand side of the barrel-extension 11 and turns upon a pin 114, a spring 115 coacting with its forward end to exert a constant effort to swing its rear end inward into the path of the forward end of the bolt 19, but the rear end of the part being formed with a bevel 116, is engaged by the cartridges as they rise in the magazine such a way that the rear end of the part is kept pushed outward against the tension of the spring 115 so as to clear the bolt 19. Soon, however, as the last cartridge has been fired and the gun opens as before, the spring 115 asserts itself to turn the part 112 on its pivot and throw its rear end into the path of the forward movement of the bolt, where the bolt is stopped, thus indicating to the user of the arm that there are no more cartridges in the gun. In order, however, to provide for closing the gun without putting any more cartridges in the magazine, I furnish a finger-piece 117 projecting through the right hand side wall of the receiver 7 and located in position to engage with the forward end of the cartridge-indicator 112, the finger-piece having a spring shank 118 by means of which it is secured in place by a screw 119. Ordinarily the finger-piece exerts no pressure on the part 112.

ch it is held by its spring shank in the finger-piece is pushed in comes the tension of its spring ie tension of the spring 115 and ut 112 on its pivot 114, whereby of the part 112 is removed from the bolt 19 which may then be rd into its closed position. ection of the spent shells upward ejection-opening 120 in the top er, I employ an ejector 121 (Figs. ve) located in a circular chamber g rearward into the forward end h-block 19. At its forward up- ie ejector is formed with a notch eception of the lower portion of a spent shell into the path of ector is allowed to rise by the a notch 124 in the lower face of (Fig. 12) below the center of ector is directly located. For ector its forward impulse, it is an operating lug 125 extending right into the path of a shoulder at the rear end of the right hand arrel-extension. Just before the sion reaches the limit of its for- sion, the shoulder 126 impinges inst the rear face of the lug 125 he ejector to jump forward, as it deliver so much of a blow upon the is to drive the same upward out

For the retention of the ejector is formed with a rearwardly ex- n 127 having a locking-notch 128 locking-rib 129 formed upon the : 26) of the breech-lock 23, the ing into the groove 128 through tion of the chamber 122 with the sion 31 of the opening 30 in the the reception of the breech-lock the breech-lock is turned by the position for removal from the the rib 129 is brought into regis- the slot 130 leading out of the ch 128, whereby the ejector may own forward out of the chamber e other hand, the ejector being in chamber 122, is locked therein by n of the breech lock 23 into its position. At its forward end the rmed with a depending blade-like (Figs. 52 and 53) having its for- beveled and designed to reach and engage with the top-most car- the same is pressed by the spring urtridge-carrier 18 up against the of the cartridge-stop ribs 15 and arrel-extension 11. This down- ing of the ejector is made nec- ie fact that the forward end of the k itself does not reach down far engage with the top-most shell me is stopped by the ribs 15 and e located in a plane below the in-

curved side walls of an ordinary box-maga- zine. Therefore the shell is first engaged not by the block itself, but by the finger 121^a and pushed forward thereby until its rear end passes the forward end of the ribs 15 after 70 which the shell is lifted up in front of the breech-block proper which then takes it and pushes it into the gun-barrel. The extractor (Fig. 3) employed in my approved gun may be of any improved construction. As shown, 75 it consists of a hook 131 located in a recess 132 in the breech block 19, mounted on a pin 133 and operated by a spring 134.

For the loading of the first cartridge into the gun barrel, and for the manual operation 80 of the gun thereafter when necessary, I employ a sliding handle 135 (Figs. 35 to 38) formed at its forward end with wing-like finger pieces 136 which overhang, as it were, the top of the receiver on which the handle 85 slides longitudinally back and forth. To se- cure the handle in place it is formed in its lower face with two parallel undercut grooves 137 receiving corresponding guide-ribs 138, 138, formed in the top of the re- 90 ceiver and separated by a slot 139 provided for the clearance of a lug 140 depending from the extreme forward end of the handle in po- sition to engage with the forward face of a lug 141 formed upon the rear end of the lock- 95 ing slide 24, the lug 141 moving back and forth in the slot 139. Under this construc- tion the sliding handle acts only when moved from front to rear, whereby the gun is opened. The forward movement of the 100 sliding handle is limited by means of a stop screw 142 mounted in its extreme rear end and engaging with a shoulder 143 at the for- 105 ward end of a shallow groove 144 in the ex- treme rear end of the receiver. In order that the locking handle may not be displaced by the recoiling of the gun, I provide it with a latch 145 located in a slot 146 formed in its right hand finger-piece 136, this latch being mounted upon a pivot 147 and hooking over 110 the forward end of the right hand guide rib 138, in which position the latch is held by a spring 148. When the handle is grasped for its operation, the latch 145 is swung so as to disengage it from the rib 138, thus releasing 115 the handle preparatory to its being drawn backward for opening the gun.

It is apparent that in carrying out my in- vention some changes from the construction herein shown and described may be made. 120 I would therefore have it understood that I do not limit myself thereto but hold myself at liberty to make such departures there- from as fairly fall within the spirit and scope of my invention.

I claim:—

1. In an automatic box-magazine firearm, the combination with a receiver, of a recoil- ing barrel-extension mounted for movement back and forth therein, a recoiling barrel 130

- mounted in said barrel-extension, a barrel-closing spring, a breech-closure, a breech-closing spring, a swinging box-magazine constructed to feed the cartridges directly upward into the center of the barrel-extension, and means independent of the magazine for stopping the cartridges in position to be pushed forward by the breech-closure into the gun-barrel after they have been fed out of the magazine, whereby the magazine may be swung into its open and closed positions without moving the breech-closure into its open position against the tension of its spring.
2. In an automatic box-magazine firearm, the combination with a receiver, of a recoiling barrel-extension mounted therein for movement back and forth, a recoiling barrel mounted in said barrel-extension, a barrel-closing spring, a breech-closure, a breech-closing spring, a swinging box-magazine constructed to feed the cartridges directly upward into the center of the barrel-extension, and means carried by the recoiling barrel-extension for stopping the cartridges in position to be pushed forward by the breech-closure into the gun-barrel after they have been fed out of the magazine, whereby the magazine may be swung into its open and closed positions without moving the breech-closure into its open position against the tension of its spring.
3. In an automatic box-magazine firearm, the combination with a receiver, of a recoiling barrel-extension mounted for movement back and forth therein, a recoiling barrel mounted in said barrel-extension, a barrel-closing spring, a breech-closure, a breech-closing spring, a swinging box-magazine, and cartridge-stop ribs located in the barrel-extension to stop the cartridges in position for being pushed forward by the breech-closure into the gun-barrel after they have been fed out of the magazine, whereby the magazine may be swung into its open and closed positions without moving the breech-closure into its open position against the tension of its spring.
4. In an automatic box-magazine firearm, the combination with a receiver having a finger-opening in its left hand side wall, of a recoiling barrel-extension mounted for movement back and forth in said receiver, a recoiling barrel mounted in the barrel-extension, a barrel-closing spring, a breech-closure, a breech-closing spring, a swinging box-magazine located in an opening formed in the right hand wall of the receiver and accessible for being pushed from left to right into its open position through the said finger-opening in the left hand wall of the receiver and constructed to feed the cartridges directly upward into the center of the barrel-extension, and means independent of the magazine to stop the cartridges in position for being pushed forward by the breech-closure into the gun-barrel after they have been fed out of the magazine, whereby the magazine may be swung into its open and closed positions without moving the breech-closure into its open position against the tension of its spring.
5. In an automatic box-magazine firearm, the combination with a receiver, of a recoiling barrel-extension mounted therein for movement back and forth, a recoiling barrel mounted in the said barrel-extension, a barrel-closing spring, a breech-closure, a breech-closing spring, a swinging box-magazine adapted in width to receive two vertical columns of cartridges and having its upper end constricted on opposite sides to feed the said cartridges directly upward into the center of the barrel-extension, and means independent of the magazine to stop the cartridges in position for being pushed forward by the breech-closure into the gun-barrel after they have been fed out of the magazine, whereby the magazine may be swung into its open and closed positions without moving the breech-closure into its open position against the tension of its spring.
6. In an automatic box-magazine firearm, the combination with a receiver, of a recoiling barrel and barrel-extension, a breech-closure, a box-magazine and a movable clip holder therefor.
7. In an automatic box-magazine firearm, the combination with a receiver, of a recoiling barrel and barrel-extension, a breech-closure, a swinging box-magazine, a movable clip holder therefor, the said clip holder being moved into its clip-holding position when the magazine is swung into its charging position.
8. In a box-magazine firearm, the combination with a receiver, of a recoiling barrel and barrel-extension, a breech-closure, a box-magazine, and a swinging clip-holder mounted thereon.
9. In an automatic box-magazine firearm, the combination with a receiver, of a recoiling barrel and barrel-extension, a breech-closure, and a box-magazine mounted in the receiver and provided with a movable spring-controlled clip-holder.
10. In an automatic box-magazine firearm, the combination with a receiver, of a recoiling barrel and barrel-extension, a breech-closure, and a swinging box magazine provided at its front and rear ends with pivots flattened in the horizontal plane to engage bearing-openings having narrow entrance.
11. In an automatic magazine firearm, the combination with the receiver and the trigger-guard thereof, of a recoiling barrel-extension mounted in the receiver for movement back and forth therein, a recoiling barrel mounted in the said barrel-extension, a barrel-closing spring, a breech-closure.

closing spring a box-magazine having and forward ends respectively piv- the said receiver and guard and com- bined to feed the cartridges directly up- into the center of the barrel-extension, means independent of the magazine to he cartridges in position for being

forward by the breech-closure into barrel after they have been fed from magazine, whereby the magazine may be into its open and closed positions by moving the breech-closure into its position against the tension of its

In an automatic box-magazine firearm, combination with the receiver thereof, of a long barrel-extension mounted for movement back and forth therein, a recoiling barrel carried in the said barrel-extension, a barrel-spring, a breech-closure, a breech-closing spring, a swinging box-magazine combined to feed the cartridges directly upward into the center of the barrel-extension, means independent thereof for stopping the cartridges in position for being pushed forward by the breech-closure into the gun-barrel after they have been fed from the magazine, and a means for holding the magazine in its open and closed positions, whereby the magazine may be moved into its open and closed positions by moving the breech-closure into its positions against the tension of its

In an automatic box-magazine firearm, combination with a recoiling barrel and barrel-extension, of a breech-closure, a box-magazine adapted to be swung into its open and closed positions irrespective of the position of the breech-closure, means carried by the barrel-extension for stopping the cartridges after they are fed from the magazine to be pushed forward by the breech-closure into the gun-barrel, and a magazine-latch for holding the magazine in its feeding and its feeding positions respectively.

In an automatic box-magazine firearm, combination with a recoiling-barrel and extension, of a breech-closure, a box-magazine adapted to be swung into its open and closed positions irrespective of the position of the breech-closure, means carried by the barrel-extension for stopping the cartridges after they are fed from the magazine to be pushed forward by the breech-closure into the gun-barrel, and a magazine-latch coacting with the forward movement of the magazine.

In an automatic box-magazine firearm, combination with the receiver thereof, of a recoiling barrel-extension mounted for movement back and forth therein, a recoil-barrel mounted in the said extension, a barrel-closing spring, a breech-closure, a breech-closing spring, a swinging box-magazine constructed to feed the cartridges directly upward into the center of the barrel-extension, means independent of the magazine for stopping the cartridges in position for being pushed forward by the breech-closure into the gun-barrel after they have been fed out of the magazine whereby the magazine may be swung into its open and closed positions without moving the breech-closure into its open position against the tension of its spring, a guide-rod mounted at its rear end in the receiver and extending forward under the barrel and encircled by the said barrel-closing spring, a guide lug depending from the barrel and having the said

breech-closing spring, a swinging box-magazine, means independent of the magazine for stopping the cartridges in position for being pushed forward by the breech-closure into the gun-barrel after they have been fed from the magazine, and a magazine-latch located at the forward end of the magazine and provided with a projecting finger-piece for its manual operation and constructed to hold the magazine in its open and closed positions, whereby the magazine may be swung into its open and closed positions without moving the breech-closure into its open position against the tension of its spring.

16. In an automatic box-magazine firearm, the combination with a recoiling barrel and barrel-extension, of a breech-closure, a box-magazine adapted to be swung into its charging position, a magazine-latch, and a plug mounted in the receiver and carrying the said latch.

17. In an automatic box-magazine firearm, the combination with a receiver, of a recoiling barrel and barrel-extension, a breech-closure, a swinging box-magazine, a pivotal clip-holder mounted in the rear wall thereof and engaged by the receiver for being swung into its retired position when the magazine is swung into its feeding position, and a spring coacting with the said holder to move it into line with the magazine when the same is swung out into its charging position.

18. In an automatic box-magazine firearm, the combination with a receiver, of a recoiling barrel and barrel-extension, a breech-closure, a swinging magazine, a clip-holder pivotally mounted in the rear wall of the magazine and provided with a semicircular stud, and a spring also mounted in the magazine and engaging with the flattened side of the stud for controlling the swinging movement of the holder.

19. In an automatic box-magazine firearm, the combination with the receiver thereof, of a recoiling barrel-extension mounted for movement back and forth therein, a recoil-barrel mounted in the said extension, a barrel-closing spring, a breech-closure, a breech-closing spring, a swinging box-magazine constructed to feed the cartridges directly upward into the center of the barrel-extension, means independent of the magazine for stopping the cartridges in position for being pushed forward by the breech-closure into the gun-barrel after they have been fed out of the magazine whereby the magazine may be swung into its open and closed positions without moving the breech-closure into its open position against the tension of its spring, a guide-rod mounted at its rear end in the receiver and extending forward under the barrel and encircled by the said barrel-closing spring, a guide lug depending from the barrel and having the said

rod extended forward through it, and a fore-stock supported at its rear end by the receiver and at its forward end by the rod.

20. In an automatic box-magazine firearm, the combination with a receiver, of a recoiling barrel and barrel-extension, a breech-closure, a swinging magazine adapted to be swung into its charging position and formed at one end with a segmental groove, and a spring-actuated magazine-latch having a nose adapted to enter the said groove.

21. In an automatic firearm, the combination with a receiver, of a recoiling barrel and barrel-extension, a breech-block, a locking-slide mounted in the breech-block and longitudinally movable independent thereof, and a rotary breech-lock mounted upon the said slide and rotated thereby for engagement with the barrel-extension and breech-block.

22. In an automatic firearm, the combination with a receiver, of a recoiling barrel and barrel-extension, a breech-block, a locking-slide mounted therein and longitudinally movable independent thereof and provided at its forward end with spiral ribs, of a rotary breech-lock mounted upon the said slide having corresponding spiral grooves and adapted when rotated to engage with the said locking extension for locking the same and breech-block together.

23. In an automatic firearm, the combination with a receiver, of a recoiling barrel and barrel-extension, a breech-block, a locking-slide mounted therein and longitudinally movable independent thereof, a rotary breech-lock mounted upon the slide and rotated thereby for coupling the barrel-extension and breech-block together, a link pivotally connected with the rear end of the locking-slide, and an action-closing spring operating through the said link.

24. In an automatic firearm, the combination with a receiver, of a recoiling barrel and barrel-extension, a breech-block, a locking-slide mounted therein and longitudinally movable independent thereof, a rotary breech-lock mounted upon the said slide, having bearing in the breech-block and adapted when rotated to coact with the breech-block and barrel-extension for locking the same together.

25. In an automatic gun, the combination with the receiver thereof, of a recoiling barrel and barrel-extension, a breech-closure, a box-magazine adapted to be swung into its open and closed positions irrespective of the position of the breech-closure, means carried by the barrel-extension for stopping the upward movement of the cartridges as they emerge from the upper end of the magazine, and a longitudinally movable ejector mounted in the forward end of the breech-closure, provided with an operating lug which is engaged by a shoulder at the rear end of the barrel-extension, and adapted to reach down be-

tween the said means and engage with the topmost cartridge for pushing the same forward until its disengagement from the said means when it rises in front of the breech closure for being pushed forward thereto into the gun-barrel.

26. In an automatic gun, the combination with a receiver, of a recoiling barrel and barrel-extension, a breech-block, a locking-slide mounted therein and longitudinally movable independent thereof, a rotary breech-lock mounted upon the said slide, coacting with the said block and barrel-extension for locking the same together and having a forward extending hub, an extractor mounted in the breech-block, and a longitudinally movable ejector mounted in the breech-block, having its rear end interlocked with the said hub and provided with an operating lug for engagement by a shoulder upon the rear end of the barrel-extension.

27. In an automatic firearm, the combination with the receiver thereof, of a recoiling barrel and barrel-extension, a non-rotatable breech-block, a non-rotatable locking-slide mounted therein for movement independent thereof, a rotatable breech-block mounted upon the said locking-slide and rotatable thereby when the breech-block starts its forward movement, and front and rear unloading levers, the rear end of the rear lever acting with the locking-slide for holding the same at the limit of its rearward excursion and the upper end of the front lever coacting with the barrel-extension for the operation of both levers thereby.

28. In an automatic gun, the combination with the hammer and trigger thereof, a sear having its rear portion made laterally flexible and terminating in a lug coacting with the trigger, and means coacting with the flexible portion of the sear every time the trigger is pulled for deflecting it to clear said lug from the trigger which thus directly controls its own release.

29. In an automatic gun, the combination with the hammer and trigger thereof, a sear having a laterally flexible shank terminating in an operating lug normally located above the trigger, and a beveled part of the shank engaging with the said lug for deflecting the same laterally to clear it from the trigger with which it can be reengaged after the trigger has been "let go".

30. In an automatic gun, the combination with the trigger and the hammer thereof, sear having a rearwardly extending laterally flexible shank terminating in an operating lug located directly over a portion of the trigger in position to be engaged thereby, a beveled pin mounted in the gun for being engaged by the said lug when the trigger is pulled, whereby the sear is laterally deflected for disengaging the said lug from the trigger which must be "let go" and allowed to

al position before the trigger he sear.

omatic gun, the combination ner having a cocking-notch, of at its front end with a nose to notch, a sear-spring, and a t with the sear, the said ham- mmered to engage as it ap- cocked position with the rear sear to insure the entrance of of into the cocking-notch in the reby in case the sear-spring the nose of the sear into the ammer, the hammer itself will ar for the entrance of the nose s notch.

omatic gun, the combination er formed in its heel with a and provided at its rear upper fin or projection, of a sear front end with a nose to enter and arranged to be engaged or projection of the hammer r is moved into its cocked posi- ar-spring, whereby in case the ls to enter the nose of the sear notch the fin or projection on will operate the sear and force of to enter the notch.

omatic firearm, the combina- receiver thereof, of a recoiling barrel-extension, a non-rotatable a non-rotatable locking-slide ein and longitudinally movable thereof, a rotatable breech-upon the said locking-slide and reby when the breech-block ard movement, an action-clos- inected with the said slide to ne forward and so rotate the g the breech-block to the bar- and a locking-slide latch pivot- in the breech-block for locking de at the limit of the rearward eof.

omatic gun, the combination ver thereof, of a recoiling-bar- el-extension, a non-rotatable a non-rotatable locking-slide ein and longitudinally movable thereof, a rotatable breech-lock u the said slide, a locking-slide l in the breech-block and coact- outward end of the locking-slide e same at the limit of its rear- n, the said latch being operated barrel-extension, as the same nit of its forward excursion, for said slide and permitting the oved forward, and an action- connected with the said slide same forward and so rotate the g the breech-block to the bar-

utomatic firearm, the combina-

tion with a receiver, of a recoiling barrel and barrel-extension, a breech-block, a locking-slide mounted therein and longitudinally movable independent thereof, coacting front and rear unlocking levers the rear end of the rear lever engaging the locking-slide to lock the same at the limit of its rearward movement and the upper end of the front lever being engaged by the barrel-extension for operating the levers, and a locking-slide latch mounted in the breech-block and coacting with the forward end of the locking-slide to hold the same at the limit of its rearward movement after the slide has been unlocked by the rear unlocking lever.

36. In an automatic box-magazine gun, the combination with a receiver thereof, of a recoiling-barrel and barrel-extension, a breech-block, a box-magazine, and a spring-actuated cartridge-indicator mounted in and moving back and forth with the said barrel-extension, located in the path of the cartridges as they are fed out of the magazine, and normally held in its retired position by the cartridges themselves, and released by the feeding of the last cartridge from the mag- azine for being thrown by its spring into position for stopping the breech-block in its for- ward movement.

37. In an automatic box-magazine gun, the combination with a receiver, of a recoiling barrel and barrel-extension, of a breech-block, a box-magazine, a spring-actuated cartridge-indicator mounted in and moving back and forth with the said barrel-exten- sion, located in the path of the cartridges as they are fed out of the magazine and nor- mally held in its retired position by the cartridges themselves and released by the feed- ing of the last cartridge from the magazine for being thrown by its spring into position for stopping the forward movement of the breech-block, and a finger-piece projecting outward through the said receiver for manu- ally operating the said cartridge-indicator.

38. In an automatic gun, the combination with the receiver and action mechanism thereof, of a long sliding handle longitudinally arranged upon and interlocked with the top of the receiver and connected at its forward end with the action-mechanism of the gun for the manual operation thereof.

39. In an automatic firearm, the combina- tion with the receiver and action-mechanism thereof, of a long longitudinally arranged sliding handle mounted directly upon the top of the receiver and formed with under- cut grooves receiving guide ribs formed upon the receiver and adapted at its forward end to be connected with the action mechanism for the manual operation thereof.

40. In an automatic gun, the combination with a receiver, of a recoiling barrel and barrel-extension, a breech-block, a locking-slide mounted therein, and a sliding handle

mounted directly upon the top of the receiver and adapted at its forward end to be connected with the said locking-slide for the manual operation thereof.

- 5 41. In an automatic gun, the combination with a receiver, of a recoiling barrel and barrel extension, a breech-block, a locking-slide mounted therein, and a sliding handle located directly upon the top of the receiver with which it is interlocked and adapted at its forward end to coact with the said lock-

ing-slide for the manual operation of the gun and provided at its forward end with a lever whereby it is normally connected with the receiver.

In testimony whereof, I have signed the specification in the presence of two subscribing witnesses.
